L. Simford Hanmer

UNITED STATES PATENT OFFICE.

HARVEY V. BASLEY, OF JERSEY CITY, NEW JERSEY.

SAFETY CLASP.

1,415,509.

Specification of Letters Patent. Patented May 9, 1922.

Application filed July 23, 1920. Serial No. 398,527.

To all whom it may concern:

Be it known that I, HARVEY V. BASLEY, a citizen of the United States, residing at Jersey City, in the county of Hudson and

5 State of New Jersey, have invented certain new and useful Improvements in Safety Clasps, of which the following is a specification.

This invention relates to a safety clasp 10 for breast pins, bar pins, and the like, the same being an improvement over the safety clasp shown and described in my pending application Serial No. 354,391, filed Jan. 27, 1920.

15 An object of the present improvement is to provide a clasp which is more efficient and at the same time more attractive than the clasp shown and described in said pending application.

20 More particularly an object of the present improvement is to so design the pin of the device that a fully efficient degree of resiliency is afforded in proper locality so as to render the engagement of the pin with 25 its post at once easy of accomplishment and efficient in the performance of its office.

A further object is to so form the pin as to present increased difficulties in the way of accidental disengagement of the pin 30 in use.

Other objects and aims of the invention, more or less specific than those referred to above, will be in part obvious and in part pointed out in the course of the following 35 description of the elements, combinations, arrangements of parts and applications of principles, constituting the invention; and the scope of protection contemplated will be indicated in the appended claims.

40 In the accompanying drawings which are to be taken as a part of this specification, and in which I have shown merely a preferred form of embodiment of the invention:

45 Figure 1 is a perspective view of a breast pin showing the clasp connected therewith constructed in accordance with this invention.

50 Figure 2 is a bottom plan view of the parts seen in Fig. 1.

Figure 3 is an enlarged transverse sectional view taken substantially upon the plane of line III of Fig. 2.

55 Figure 4 is a side elevational view of the parts seen in Fig. 1, and

Figure 5 is a diagrammatic view illustrating the manner in which the clasp of this invention is effective as a safety holder for the breast pin.

Describing in detail the structure which is 60 illustrated in the drawings forming a part hereof, the reference character L indicates the body of the breast pin, which, for convenience, is illustrated as a simple bar pin. The clasp with which this invention is concerned is arranged at the under surface of 65 the body and consists of a pin portion G and a post H.

The pin G is pivotally mounted, as at 1, upon a suitable supporting bracket 2 at one 70 end of the body L. The opposite end of the pin is bent over upon itself so as to provide two legs, or portions, as 3 and 4. A suitable space 5 is thus provided between 75 the portions 3 and 4 to receive the post H.

The material from which the pin is formed is of such character that the parts 80 3 and 4 are resilient relative to each other so that they can spring apart sufficiently to allow them to snap over the ball shaped head 6 of the post and to grip upon the reduced neck portion 7 of the post.

The post is so placed with respect to the 85 portions 3 and 4 of the pin that the portion of the pin, as 8, which connects the portions 3 and 4 is spaced a considerable distance beyond the post, thus providing an efficient finger grip portion by which the user may readily snap the portions 3 and 4 into and out of engagement with the neck of the post. 90 By properly spacing the portion 8 from the post a correct advantage may be taken of the resiliency of the material for providing efficient cooperation between the pin and the head 6; that is to say, that by disposing the portion 8 further from the post, a greater degree of resiliency is provided between the portions 3 and 4 at the points where said portions engage the post than if the part 8 be nearer to the post.

100 It should be noted that a user, in pressing upon the portion 8 to swing the pin out of engagement with the post, presses with equal force against both the portions 3 and 4, thus causing said portions to readily disengage from the head of the post.

On the other hand, if, while the main portion of the pin between the bracket 2 and the post is in engagement with a garment, a pull should be applied to the body 110

L tending to draw the head 6 out from between the portions 3 and 4, this pull would be resisted almost solely by the portion 3. The portion 4, having an equal grip with 5 the portion 3 upon the neck of the post, will tend to cling to its position upon the neck 7 and will thus produce a binding action of the portions 3 and 4 against opposite sides of the head preventing the head from 10 being released unless a strong pull is applied to the post.

Likewise, if the portion of the garment engaged by the pin between the pivot and the post is of greater thickness than the 15 space between the pin and the body L so that there is a constant pressure tending to move the pin out of engagement with the post, this pressure will be applied principally to the portion 3, leaving the portion 4 20 to produce a binding action resisting release of the post as just described.

The extreme end of the portion 4 of the pin, is of course, pointed as at 9.

In use, the pin is connected to a garment 25 by introducing the point 9 into the garment and then moving the pin so that a proper portion of the garment follows around the portion 8 of the pin and moves on to the intermediate or main portion of the pin 30 between the pivot and the post. The post is then snapped down between the portions 3 and 4 of the pin, and the operation is complete.

If two portions of the garment, for instance the opposite edges of a lady's coat or 35 waist, are to be connected, one portion is threaded on to the pin as just described, and the second portion threaded on likewise, the post being snapped down after the second 40 portion is properly threaded.

The portion 4 forms a hook at the end of the pin which is always effective for preventing accidental disengagement of the pin from the garment. Where, for instance, 45 two portions of a garment are threaded on to the pin, as just referred to, this hook serves to positively retain the portions of the garment in proper position even if the post should be disengaged. Not only are 50 the portions of the garment held properly connected, but also the pin itself is prevented from falling out and becoming lost. If the post becomes disengaged from the pin the body L will still remain connected to 55 the pin by means of the pivot 1. The weight of the body thus connected at the end of the pin opposite to the hook 4 serves to hold the hook in full engagement with the garment until purposely and carefully re- 60 moved.

All of the features and advantages thus far set forth are present in the structure of the pending application, though to a lesser degree than in the structure herein illus- 65 trated.

A feature of the present improvements resides in making the post engaging portion of the pin comprising the portions 3 and 4 relatively thinner than the main portion, as 10, of the pin. It has been found that by 70 proportioning the parts in this manner a suitably stiff material may be employed such as in its thicker portion 10 it is amply stiff to resist ordinary bending strains in use, while in its thinner portions 3 and 4 75 it is of a suitably flexible character so that the parts 3 and 4 are capable of a considerably greater resilient movement relative to each other than if they are made of material of equal size with a main portion. 80 The increased resiliency of the parts 3 and 4 relative to each other, as compared with the resiliency of said parts as in the structure of the pending application, adds greatly to the efficiency of said parts in all 85 of their functions. They are more easily snapped over the head of the post. They are capable of sinking into a deeper neck of the post. And they bind more efficiently against the head when pressure occurs upon 90 the part 3 which might undesirably release them from the head.

A further feature of the present improvements resides in the formation of a shoulder, as 11, upon the pin at the juncture of the 95 part 3 with the main part 10. This shoulder is placed so that it has several values, among which may be mentioned particularly, first, that it provides a relatively restricted opening 12 between itself and the adjacent point 100 9 of the pin, which restriction is effective in preventing accidental detachment of the pin from a garment, and second, that it places the main part 10 of the pin substantially in alignment with the post, thus adding 105 materially to the attractiveness of the device.

While it is preferable, to the fullest attainment of the advantages of this invention, to have both of the post-engaging parts 110 3 and 4 of the pin reduced in cross sectional dimensions, as compared with the main part 10, yet it will be apparent that a reduction of either one of said parts 3 or 4 or even of the part 8 may be sufficient to the 115 attainment of satisfactory results in different instances.

As minor changes could be made in this construction without departing from the scope of the invention as defined in the following claims, it is intended that all matter contained in the above description, or shown in the accompanying drawings, shall be interpreted as illustrative only and not in a limiting sense.

Having thus described my invention, what I claim as new and desire to secure by Letters Patent is:-

1. A clasp of the type indicated, comprising a pin, a pivotal support for the pin, a 130

post to be engaged by the pin, the pin comprising a main part having at its free end spaced portions arranged to snap into engagement with opposite portions of the post, and said spaced portions being of reduced cross sectional dimensions as compared with the main part of the pin, substantially for the purpose set forth.

2. A clasp of the type indicated, comprising a pin, a pivotal support for the pin, a post to be engaged by the pin, the pin comprising a main part and a post engaging part, the post engaging part having portions of its length bent to lap over another portion of itself and to provide an opening between the lapping portions adapted to receive the post, and at least one of the lapping portions of the pin being reduced in cross sectional dimensions as compared with the main part 20 of the pin.

3. A clasp of the type indicated comprising a pin, a pivotal support for the pin, a post to be engaged by the pin, the pin comprising a main part and a post-engaging 25 part, the post-engaging part comprising a portion of the pin bent back upon itself to provide an opening adapted to receive the post, the post having a head thereon, the opening being of less width than the head, 30 the post-engaging part of the pin being of resilient material whereby to render the walls of the opening resilient and adapted to snap over the head, and there being a shoulder formed upon the pin at the juncture of

the main part and the post-engaging part 35 thereof.

4. A clasp of the type indicated comprising a pin, a pivotal support for the pin, a post to be engaged by the pin, the pin comprising a main part and a post-engaging 40 part, the post-engaging part comprising a portion of the pin bent back upon itself to provide an opening adapted to receive the post, the post having a head thereon, the opening being of less width than the head, 45 the post-engaging part of the pin being of resilient material whereby to render the walls of the opening resilient and adapted to snap over the head, and the material of the pin being shaped to provide a restricted passage into said opening adjacent the point of the pin.

5. A clasp of the type indicated comprising a pin, a pivotal support for the pin, a post to be engaged by the pin, the pin having its end portion bent over upon itself to provide a hook the opposite parts of which are spaced away from each other to provide an opening adapted to receive the post, and the pin being shaped to provide a restricted 55 60 passage into said opening.

In testimony whereof I affix my signature in the presence of two witnesses.

HARVEY V. BASLEY.
